UNITED STATES PATENT OFFICE.

CHARLES P. NUTTER, OF MALDEN, MASSACHUSETTS, ASSIGNOR TO N. G. WOOD & SONS,
OF BOSTON, MASSACHUSETTS, A FIRM.

DESIGN FOR A STEIN.

40,395.

Specification for Design.

Patented Dec. 14, 1909.

Application filed August 13, 1909. Serial No. 512,931. Term of patent 7 years.

To all whom it may concern:

Be it known that I, CHARLES P. NUTTER, a citizen of the United States, residing at Malden, in the county of Middlesex and State of Massachusetts, have invented a new, original, and ornamental Design for Steins, of which the following is a specification, reference being had to the accompanying drawing, forming part thereof.

The drawing represents a perspective view

of a stein embodying the features of the present invention.

I claim:

The ornamental design for a stein, as shown.

CHARLES P. NUTTER.
